PIVOTAL BOTTOM SUPPORTING PLATE

William H. Uhl, Penfield, N. Y., assignor to Commercial Controls Corporation, Rochester, N. Y., a corporation of Delaware

Application August 22, 1950, Serial No. 180,715

3 Claims. (Cl. 216—1)

1

This invention relates to a base structure, and more particularly to a pivotal bottom supporting plate for a mail matter handling machine such as disclosed in my copending application Serial No. 140,407 filed January 25, 1950.

A machine of the type disclosed in the above mentioned pending application is designed for handling envelope mail. Within a single compact unit provision is made for opening sealed envelopes, for moistening the flap of an envelope to be sealed, and for affixing a stamp in the proper place.

Among the objects of this invention is to provide a pivotal bottom supporting plate for a mailing machine of the type described which will lend more flexibility to the device. Another object is to provide a base or supporting plate adapted to receive for stamping envelopes having the usual contents of but a few sheets of paper, and yet capable of expanding to permit a thick envelope such as one containing bulky documents, to be inserted and stamped. A further object is to provide a supporting plate having provision for partial access at the bottom so that the operator may if desired remove stamps from the machine by hand for use on packages and miscellaneous items. A still further object is to provide a mailing machine base plate which is sturdy in construction, economical, attractively designed, and cushioned along the underside to prevent marring and to rest with traction on a table surface. These and other objects will be in part apparent and in part pointed out hereinafter.

The invention accordingly consists in the features of construction, combinations of elements, arrangements of parts and the relation and order of each of the same to one or more of the others, all as will be illustratively described herein, and the scope of the application of which will be indicated in the claims.

In the drawings in which one form of my invention is shown:

Fig. 1 is a perspective view of a mail matter handling machine equipped with a pivotal bottom supporting plate;

Fig. 2 is an enlarged fragmentary sectional view taken along line 2—2 of Fig. 1; and

Fig. 3 is a plan view taken along line 3—3 of Fig. 2.

Similar reference characters refer to similar parts throughout the several views of the drawings.

In one embodiment of my invention the mailing machine base structure comprises a flat main plate extending over a portion of the bottom of

2

the mailing machine and having flanges around three sides for legs, hinge tabs underneath, and suitable holes to secure the plate with bolts. An envelope supporting member extends over the remainder of the bottom surface and is pivotally attached to the main plate and stepped down to leave an opening in which envelopes may be inserted. Leaves along the side are associated with the main plate hinge tabs to form the pivotal connection between the two parts, and one leaf projects beyond the hinge point away from the body of the envelope supporting member to serve as a stop to limit its degree of movement. The outer edge of the envelope support is flanged to provide a supporting leg, and a rubber cushion strip is fitted over the lower edge of this flange; another rubber strip is fitted around the peripheral flange of the main plate. Accordingly the mailing machine rests squarely on a cushioned base structure.

The main plate is secured to the underside of the mailing device, but the envelope supporting member is free to pivot to a degree limited upwardly approximately to horizontal position 25 where its upper section strikes the main plate, and limited downwardly by the hinge leaf stop projection. This action allows expansion of the envelope receiving opening. The mailing device itself has a projecting plunger by which the stamp affixer is operated and this plunger serves 30 as a convenient handle for lifting the entire unit. Thus to expand the envelope opening it is only necessary to grasp the plunger and tilt the machine to one side causing it to pivot on one edge or leg of the main plate. Because of the hinge joint on the main plate the envelope supporting member will remain stationary. The envelope opening thereby is increased in size and a bulky envelope may be inserted for affixing a stamp thereto when the machine is lowered and actuated, or the operator may with his fingers reach 35 in and remove stamps from the bottom of the mechanism. A sturdy and inexpensive bottom plate structure is thus provided which further adds to the flexibility of a compact mail handling machine.

Referring now to the drawings, in Fig. 1 there is shown at 10 a mail matter handling machine as is disclosed and described in detail in my copending application mentioned before. A device 12 for slitting the edge of an envelope is positioned on the left side above an envelope flap moistener 18, while the stamp affixing mechanism 20 is located inside casing 22 on the right. The envelope slitter is manually operated by a knob

14 and the stamp affixer by a plunger 16, all as described in the said copending application.

The base structure is generally indicated at 24 and comprises a main plate 26 secured to the bottom of machine 10 by bolts 28 extending through suitable holes 29 (Figs. 2 and 3), and an envelope supporting member 30 pivotally connected to plate 26. A hole 31 is provided in both plate 26 and member 30 as clearance for the lower end of supporting column 33 of machine 10. Three outer edges 32a, 32b and 32c of plate 26 are flanged downwardly to form leg structures 34 on which the machine rests, while hinge tabs 36a and 36b project vertically below the supporting surface and are provided with holes for receiving a shaft 38 by which envelope supporting member 30 is hinged. Plate 26 extends only to a point 40 along the bottom of machine 10, thus leaving an open area beyond the plate through which stamp affixing device 20 operates.

Envelope supporting member 30 has leaf portions 44a and 44b which fit adjacent the inside of hinge tabs 36a and 36b respectively. Holes are provided in these leaves in line with the tab holes and shaft 38 extends through both structures. A collar 46 at each end of shaft 38 prevents disassembly of the base structure. A flat portion 43 of member 30 rests under and against plate 26 from the hinges to point 40, and is then stepped down at 50 to an envelope supporting section 52 which is flat and parallel to bottom cover 42 of machine 10. A flanged edge 54 provides the right hand supporting leg for member 30, and rubber strips 56 embracing the lower edges of flanges 34 and 34 cushion the machine base.

Thus there is formed an opening 58 between cover 42 of machine 10 and envelope supporting surface 52 of member 30 into which an envelope may be inserted for the purpose of pasting a stamp thereto when plunger 16 is pressed downwardly. Cover 42 is provided with a suitable opening 41 (Figs. 1 and 2) through which stamp affixing mechanism 20 operates. Point 40 to which plate 26 extends is located to the right of the center of gravity of machine 10 so that ordinarily all weight is supported squarely on leg structures 34; thus flange 54 merely holds section 52 in parallel relation to cover 42, step 50 being such, in the present embodiment of the invention, that envelope supporting surface 52 bisects the distance between cover 42 and the table surface on which base structure 24 rests. This construction permits an envelope the thickness of opening 58 to be inserted and stamped without shifting machine 10, but when a thicker piece of mail is handled the operator need only grasp plunger 16 and pivot machine 10 on edge 32b (Fig. 2) of plate 26 to expand opening 58, since member 30 is hinged to plate 26 and will not pivot with the rest of the machine. When machine 10 is lowered, cover 42 rests against the envelope while flange 54 supports some weight due to machine 10 being canted to the left as viewed in Fig. 1. Then when plunger 16 is actuated a stamp will be pasted to the envelope in the usual fashion. The arrangement thus provided has an added important feature of preventing affixing of stamps to an irregular, wrinkled surface, because the weight of the machine 10 and pressure resulting from actuation of plunger 16 causes the portion of bulky envelopes exposed under opening 41 to be flattened by pressing against section 52 underneath, which section is supported by flange 54. Therefore, a neat thorough binding is always pro-

vided between stamp and envelope regardless of contents.

To limit the amount that member 30 pivots relative to plate 26, hinge leaf 44a is provided with an extension 60 extending a short distance beyond shaft 38 under plate 26. Thus, as machine 10 is lifted member 30 pivots relative to plate 26 until end 60 abuts the underside of plate 26. This prevents an inordinate amount of relative swinging of member 30, and yet permits sufficient expansion of opening 58 for bulky envelopes to be inserted, or for the fingers of the operator to reach in and grasp loose stamps from stamp affixing device 20 at opening 41 in cover 42.

Member 30 has three markings 61 engraved along the edge and over flange 54, with numerals "1", "2" and "3" placed thereon, to indicate proper location with respect to opening 41 of an envelope to be stamped. The right edge of an envelope should be placed along marking 61 numbered "1" when a first stamp is affixed. If a second stamp is needed for more postage, the envelope is then shifted to marking "2" and when plunger 16 is depressed a second stamp will be posted beside the first. Similarly a marking numbered "3" defines envelope position when placing a third stamp beside the second.

Accordingly by a novel mechanical arrangement, I provide a base structure for mail matter handling machines and the like which combines with the features of an attractive stand, the utility and added flexibility resulting from an expandable envelope stamping opening, thereby increasing normal capacity of the machine.

Since many possible embodiments may be made of the features of the above invention, and since the examples herein described may be varied in many particulars, it is to be understood that all matters hereinabove set forth or shown in the examples are to be interpreted as illustrative and not in a limiting sense.

Having described my invention, what I claim as new and desire to secure by Letters Patent is:

1. The combination of a portable composite mail handling machine having a bottom with a stamp dispenser opening therein, a stand secured to said machine and laterally spaced from said dispenser opening for elevating said machine above a table or the like, and an envelope supporting member pivotally connected to said machine and extending below said stamp dispenser opening to provide a space between the supporting member and said bottom which may be expanded by tilting or lifting said machine manually to accommodate envelopes of different thicknesses.

2. The combination of a portable composite mail handling machine having a substantially flat underside with a stamp dispenser opening therein, a stand secured to said underside for supporting said machine above a table or the like, and a plate extending below said stamp dispenser opening to provide an expandable opening into which an envelope may be inserted for stamping, said plate having one end pivotally attached to said stand and its other end adapted to rest on said table, whereby an envelope thicker than said expandable opening at its normal position is compressed by dead weight of said machine during stamping.

3. The combination of a stamp affixing machine including stamp affixing mechanism and a stamp dispenser opening adjacent one end thereof, means for supporting said machine with the bottom thereof spaced from a table or the like, and a plate pivotally connected to said machine

and extending beneath said dispenser opening, the free end of said plate being shaped to rest on said table to support the plate in substantially parallel relationship with said bottom of said machine so that the opening between said plate and said machine may be varied to accommodate envelopes of different thicknesses by tilting the machine to raise said bottom from said plate.
